APPARATUS FOR ACCELERATING ELECTRICALLY CHARGED PARTICLES

Rolf Wideröe, Ennetbaden, Switzerland, assignor
to Aktiengesellschaft Brown, Boveri & Cie,
Baden, Switzerland, a joint-stock company

Application March 8, 1951, Serial No. 214,471
In Switzerland December 1, 1949

9 Claims. (Cl. 313—62)

1

This invention relates to accelerators for electrically charged particles such as electrons wherein the particles are forced to travel an orbital path of substantially constant radius while at the same time being constantly accelerated along the path, and is a continuation-in-part of my application Serial No. 198,547 filed December 1, 1950, and now abandoned.

One type of accelerator, known generally as a "betatron" or "ray transformer," to which the present invention can be applied, is comprised of an evacuated annular tube into which electrons are introduced from an electron emissive cathode, and a magnetic system which produces a magnetic field varying with time having a spatial distribution such that the injected electrons are accelerated along a substantially circular orbit within the tube by magnetic induction effects. The magnetic field divides into two components. One component known as the induction field is responsible for acceleration of the electrons around the orbit, and the other component known as the control field produces an increasing centripetal force upon the electrons which is designed to match the increasing centrifugal forces of the electrons as the latter increases in velocity thus maintaining the electrons on a circular path of substantially constant radius. The electrons reach enormously high energy levels as a result of their acceleration and at the end of the acceleration phase can be diverted from the orbit and caused to impinge upon an anode to produce X-rays or used for other purposes.

The betatron type of accelerator usually incorporates a stabilizing device for restoring to the prescribed circular orbit those electrons which deviate from it. Such stabilization can be achieved for example by establishing a gradient in the control field such that the strength of field decreases outwardly with increasing radius of the electron path, and a full discussion of the apertaining theory can be found in U. S. Patent No. 2,103,303, issued December 28, 1937, to Max Steenbeck. The stabilization attributable to the decrease in field strength is effective only within a limited vicinity of the precalculated circular orbit for electron travel, known generally as the circle of equilibrium, but within the effective area provides both radial and axial stabilizing force components for any electrons which leave the precalculated orbit. In the plane of the equilibrium circle, the stabilizing force has two maxima, which lie on circles located radially inward and outward respectively from the circle of equilibrium.

2

Heretofore, it has been the general practice to locate the anode and its necessary supporting structure, against which anode the stream of electrons is caused to impinge for the production of hard X-rays, outside of the effective area of stabilization, that is, outside of the two limit circles of maximum stabilizing forces, since it was thought that too many electrons would be lost from the stream by impingement were an obstacle to be placed anywhere in the same general area where electrons might be expected to travel during their acceleration phase.

Experience, however, has shown that the yield of hard X-rays for example from a betatron varies somewhat inversely as the radial distance which the electrons must travel from the circle of equilibrium to reach the anode. One possible explanation for this undesirable effect is that in the vicinity of the maxima of the stabilization forces, local disturbing fields enter into the control field space from without with the result that the inner and outer circles of maximum stabilizing force which define the effective area of electron stabilization lie closer to the circle of equilibrium than is calculated.

The general objective of this invention is to provide an improved arrangement for the anode within the annular tube that will assure a maximum yield of accelerated electrons available for impingement against the anode and such objective is achieved by employing a support therefore extremely thin in the dimension perpendicular to the plane of the circle of equilibrium and which locates the anode in the plane of the equilibrium circle at a point between the limits of one half and four fifths of the distance to the equilibrium circle from either the inner or outer limit circles of maximum stabilizing force.

The foregoing as well as other objects and advantages inherent in the invention will become more apparent from the following description and accompanying drawings illustrating two practical embodiments of the invention.

In the drawings,

Fig. 1 is a view in central vertical section of an accelerator for electrically charged particles known as a betatron, wherein electrons are accelerated by magnetic inductive effects exclusively, to which the invention has been applied.

Fig. 2 is a view partly in horizontal section and partly in plan of the accelerator shown in Fig. 1;

Fig. 3 is a curve used in explaining the invention;

Figs. 4 and 5 are views in top plan and side elevation of the anode and its supporting structure drawn to an enlarged scale; and

Figs. 6 and 7 are views similar to Figs. 4 and 5 illustrating a somewhat modified supporting structure for the anode.

Referring now to Figs. 1-5 in particular, the electron induction accelerator, which is symmetrical about a vertical axis $a-a$, is comprised of a magnetic structure 10 made up from steel laminations of appropriate contour and includes a pair of confronting cylindrical induction poles 11-11' separated by air gap 12 located concentrically along axis $a-a$, and a pair of confronting annular control poles 13-13' separated by air gap 14, the control poles being located radially outward from the induction poles and also concentric with axis $a-a$. The confronting faces of the control poles are preferably tapered in such manner that the air gap 14 increases as measured in the radially outward direction from axis $a-a$, thus effecting a corresponding decrease in strength of the control field.

Yoke members 15 complete the magnetic circuit for the time varied magnetic field set up in the control and induction poles. A winding preferably split into two annular coil sections 16, 16' surrounding the upper and lower control poles 13-13' respectively and wound in the same direction are connected in series for energization from a source of alternating current of suitable frequency such as for example 100 cycles/sec., such source being indicated simply by terminals 17. An annular evacuated tube 18, preferably of glass, is disposed symmetrically in the air gap 14 between the control poles 13-13'. The time-varied current in energizing coils 16-16' produces the time-varied magnetic field previously mentioned. The induction component of this field responsible for electron acceleration passes through induction poles 11-11' across air gap 12, and the control component responsible for maintaining the electrons on a circular path of constant radius passes through poles 13-13' across air gap 14. In Figs. 1 and 2, the circular path or circle of equilibrium is designated k and its radius indicated by R_0 , the plane containing the equilibrium circle k being perpendicular to axis $a-a$.

As previously explained, all of the electrons do not always adhere strictly to the path k but rather deviate from the same. In order to stabilize the electron path, the control field is made to decrease in the radial direction by tapering the faces of the control poles 13-13'. The stabilization force P attributable to this radial gradient in the control field has a characteristic as shown by the curve in Fig. 3 which shows the course of the force in a plane perpendicular to the equilibrium circle k . At the circle of equilibrium k , radius R_0 , force P is zero. In a direction radially outward from circle k , the stabilizing force P rises uniformly in one direction reaching a maximal along an outer limit circle m of radius R_a . In the direction radially inward from circle k , the stabilizing force P rises uniformly in the other direction reaching a maximal along an inner limit circle n of radius R_i . The force P drops quickly after reaching the maximal at the inner and outer limit circles. For locations R_a and R_i , there applies the condition $R-B=\max$, or

$$\frac{R_a dB}{B dR} = 1$$

B being the strength of the control field.

The cathode 20 constituting the source of the electrons to be accelerated together with the necessary accessories is located within a housing 21 disposed radially inward of the inner stabiliz-

ing limit circle n . In an experimental model which has proven very satisfactory, a very thin plate 22 whose dimension in a direction perpendicular to the plane of the circle of equilibrium 5 is at most one-tenth of a millimeter projects laterally from housing 21 in a radially outward direction for about 15 millimeters and at the outer end thereof the plate 22 supports the anode 23 which is spaced from the equilibrium circle k by at least one half and by at most four fifths of the radial distance d to the equilibrium circle n . The plate 22 which may be made from platinum or a platinum-iridium alloy preferably is wider at its point of attachment to housing 21 than at the end carrying anode 23 for easier attachment to the housing and also in order to place its mechanical inherent vibration frequency as high as possible above the frequency of the current used in energizing the coils 16-16'.

In the plane perpendicular to the plane of the equilibrium circle k , the support plate 22 therefore presents only a very small area and constitutes, during a small, initial fraction of 25 the acceleration period during which the electrons still deviate appreciably from the equilibrium circle, only a very small obstacle to electron travel within the total area of stabilization. Consequently the number of electrons lost 30 from the stream because of impingement with support 22 is practically negligible. During the subsequent longer remainder of the period in which the electrons are accelerated the deviation of the electrons from the equilibrium circle 35 becomes much smaller and none of the electrons strike the support 22 or anode 23.

Since the electrons are scattered as they enter the anode 23, it is advisable to give the anode 40 which preferably consists of platinum, a somewhat larger dimension in the direction perpendicular to the plane of the equilibrium circle k than is given the support plate 22, as seen more clearly in the enlarged Figs. 4 and 5, so that the face of the anode offers to the incoming accelerated beam of electrons an area of about 45 0.25, or 0.5, or at most 1.0 square millimeter. This area is much smaller than the area of plate 22 in the same plane, the length of the plate being about fifteen millimeters. The dimension of the anode 23 and plate 22 in the direction parallel with the plane of the equilibrium circle k in the experimental model was about 2 millimeters, and the cathode 20 was located approximately the same distance from the inner limit circle n as the anode 23. The necessary control circuits by which the cathode 50 20 is energized periodically in timed relation with the variation in the magnetic field to inject a stream of electrons into the tube at the beginning of each cycle or half cycle of the alternating magnetic field have not been illustrated 55 since various arrangements are already well known and moreover are not considered essential to an understanding of this invention which concerns only the placement of the anode and cathode elements within the tube, and the support for the anode.

In the betatron type of accelerator, means must be provided for diverting the electron stream from the orbit k towards the end of the acceleration period so as to cause it to impinge against the anode 23. One practical way of accomplishing this result is to change the ratio 70 between the induction and control field components such as by effecting a partial magnetic

saturation in the magnetic circuit. In the illustrated embodiment of the invention wherein the anode is disposed radially inward of the orbit k , the induction poles 11-11' would thus each include a portion 11a, 11'a of restricted area so as to effect a partial magnetic saturation in these poles as the induction field reaches a predetermined magnitude. Thereafter the centripetal forces attributable to the control field would exceed the centrifugal forces of the electrons thus driving the electrons radially inward from the orbit k .

If desired, the cathode and its housing may be located radially outward from the outer stabilizing limit circle m in which case the anode would be disposed at a corresponding position between the outer limit circle m and the equilibrium orbit k . Such an arrangement would of course require the electron stream to be diverted radially outward from the orbit k for impingement against the anodes and could be effected by producing a partial magnetic saturation effect in the control poles.

In lieu of the support plate 22, Figs. 6 and 7 show an arrangement wherein the anode support is constituted by a U-shaped stirrup 28 whose two ends are secured to the cathode housing 27. The anode 28 is secured at the outer end of the stirrup, and like plate 22, the dimension of the stirrup in the direction perpendicular to the plane of the equilibrium circle k would be very small, that is, of the order of .1 millimeter or less so as to present as small an obstacle as possible to the run of the electrons around the orbit.

In conclusion, while I have described and illustrated my invention as applied to a betatron wherein electron acceleration is produced wholly by the principles of magnetic induction, it can be applied equally as well to other types of accelerators such as the synchrotron which employs a magnetic structure similar to that used in the betatron but uses the magnetic field produced by it principally for guiding the electron stream in the circular path. The initial acceleration of the electron stream can be effected by magnetic induction but thereafter further energy is added to the stream by causing it to traverse a resonant cavity containing a gap to which a high frequency potential is applied such as described and shown in U. S. Patent No. 2,485,409, issued October 18, 1949, to H. C. Pollock et al.

Moreover while I have shown the anode as being carried by a support secured to the cathode housing, the support could be secured in some other manner within the tube without departing from the spirit and scope of the invention as defined in the appended claim.

I claim:

1. In a device for accelerating charged particles comprising a magnetic structure including a pair of axially aligned circular control poles the faces of which are arranged in confronting relation to establish a gap therebetween, an annular tube disposed in the gap between said control poles providing therein an orbital path for acceleration of the particles, means for producing a time varied magnetic field across said gap between said control poles to confine the particles to a substantially circular path coincident with a circle of equilibrium during the acceleration phase, said pole faces being divergent in a radially outward direction whereby the strength of said field decreases in a direction radially outward from the 75

axis of said control poles to establish a stabilizing force for the particles having in the plane of said equilibrium circle two maxima lying respectively on limit circles located radially inward and outward of said equilibrium circle, an anode in said tube disposed in the plane of said equilibrium circle and spaced from the latter by at least half but not exceeding four fifths the distance to the said equilibrium circle from one of said limit circles, and a support within said tube for said anode, said support being relatively thin as measured in a direction perpendicular to said equilibrium circle.

2. A device for accelerating charged particles as defined in claim 1 wherein said anode is constituted by a body of platinum having one face disposed perpendicular to the plane of said equilibrium circle having an area not exceeding one square millimeter.

3. A device for accelerating charged particles as defined in claim 1 wherein the dimension of said anode support in a direction perpendicular to said equilibrium circle is at most one-tenth millimeter.

4. A device for accelerating charged particles as defined in claim 1 wherein the support for said anode consists of a platinum-iridium alloy.

5. A device for accelerating charged particles as defined in claim 1 wherein the support for said anode consists of platinum.

6. A device for accelerating charged particles as defined in claim 1 and which further includes a cathode housing disposed within said tube at the side of the said one limit circle away from said anode, and a cathode within said housing for producing the said charged particles, said cathode being located substantially the same distance from said one limit circle as is said anode, and said anode support being attached to said cathode housing at the end opposite that at which said anode is attached.

7. A device for accelerating charged particles as defined in claim 6 wherein the support for said anode at the end attached to said cathode housing has in the plane of the equilibrium circle a larger dimension than the end supporting said anode.

8. A device for accelerating charged particles as defined in claim 7 wherein the support for said anode is constituted by a flat plate.

9. A device for accelerating charged particles as defined in claim 1 and which further includes a cathode housing disposed within said tube at the side of the said one limit circle away from said anode, and a cathode within said housing for producing the said charged particles, said cathode being located substantially the same distance from said one limit circle as is said anode, and said anode support is constituted by a U-shaped stirrup attached by the ends thereof to said cathode housing.
